EXPANDING COLLAR

Ernest T. Straubel, Green Bay, Wis.

Application August 5, 1937, Serial No. 157,550

3 Claims. (Cl. 242—68)

The invention relates to an expansion collar for mounting on shafts and more particularly it relates to a collar adapted to be associated with the end of a tubular core and to operatively engage the core with the shaft whereby a sheet of paper or other material may be wound about the core to form a roll and the paper be unwound from the roll by the resulting rotation of the core with the shaft.

10 The cores are used as a nucleus for winding sheets of paper in compact so-called parent rolls, and in order that the roll may be rigid and adapted for control in unwinding of the paper from the parent rolls, such cores are usually constructed of stiff paper or cardboard stock. In order that the cores may be rigid and adapted for repeated use as nuclei for paper rolls, they are necessarily of substantial thickness and in general are of a composition such that they are 20 relatively expensive. In order that such cores may be rotated with a shaft serving as a spindle extending through the core, it is customary to provide an expansion collar adapted to frictionally engage the shaft with an end of the core.

25 Economy of production makes it desirable that the cores be used again and again in the winding of parent rolls, and this, in turn, requires that the collar, operatively connecting the shaft with the core, be so constructed that the core is 30 not mutilated, or otherwise rendered unfit for repeated use.

It is an object of the invention to provide an improved expansion collar of the kind described adapted to quickly connect and disconnect tubular cores with a shaft serving as a spindle in a manner such that the core is not mutilated, and whereby the core is rotated with the shaft to wind sheets of paper into compact rolls about the core as a nucleus and to unwind the sheets 40 as desired.

Another object of the invention is the provision of improvements in collars of the kind described whereby a shaft may be accurately centered in the collar and core, and the collar frictionally engage the core and the shaft at a plurality of constricted areas, whereby all possibility of the slipping of the collar relative to the shaft or the core is eliminated.

A further object of the invention is to provide 50 a collar of the kind described which is durable, simple, easily assembled, inexpensive to manufacture, and satisfactory for its intended purpose.

Many other objects of the construction herein 55 shown and described will be obvious to those

skilled in the art from the disclosure herein given.

To this end, my invention consists in the novel construction, arrangement and combination of parts herein shown and described, and more particularly pointed out in the claims. 5

In the drawing wherein like reference characters indicate like or corresponding parts:

Fig. 1 is an elevational view of a shaft equipped with two collars embodying the principles of the invention, and respectively positioned in operative engagement with the opposite ends of a tubular core of cardboard, the core and one of the collars being shown in longitudinal section; 10

Fig. 2 is a plan view of one of the collars shown in Fig. 1; and 15

Fig. 3 is a view drawn to a larger scale along the line 3—3 of Fig. 2.

Referring now more particularly to the drawing, the collars embodying the principles of the invention are designated by the numeral 10, and 20 are shown as mounted in longitudinally spaced relation on a rotatable shaft 11. The shaft 11 is operatively connected with any suitable driving element and is journaled in bearings not shown. The drawing illustrates the shaft 11 as 25 equipped with a pair of the collars 10 adapted to operatively engage the opposite ends of the tubular core 12 of cardboard or similar material. However, in practice, a single collar 10 is frequently used and a collar permanently fastened 30 to or integrally formed with the shaft is used as a substitute for the second collar 10. The shaft 11 is of smaller diameter than the inner diameter of the core 12, and serves as a spindle for rotating the core to wind a sheet of paper 35 on the core to form a roll. Illustration of the sheet of paper to be wound about the core 12 is omitted as not being necessary to an understanding of the invention. 40

Each collar 10 consists of a member 13 and a member 14 extending longitudinally of the shaft 11. The members 13 and 14 are mounted on opposite sides of the shaft 11 and are pivotally connected by a pin 15. The members 13 and 14 are preferably formed by casting from any suitable 45 metal and have their adjacent faces respectively provided with registering substantially semi-cylindrical shaped recesses 16 and 17 through which the shaft 11 extends as shown. The radius of curvature of the recesses 16 and 17 is somewhat larger than the radius of the shaft 11 to permit accurate centering of the shaft and relative tilting of the members 13 and 14 about the pin 15, as hereinafter described. 50

The outer end of the member 14 is substantially 55

rectangular in cross section and has a pair of laterally spaced projections 18 bounding a recess 19. The outer end of the member 13 comprises a generally rectangular element 20 positioned in and loosely fitting the recess 19 provided by the member 14. The pin 15 extends laterally through the projections 18 and the element 20, the pin preferably having a close fit with the projections and a loose fit in a bore 21 provided by the element.

The outside peripheries of the members 13 and 14 are substantially semi-cylindrical in shape except at their outer ends. The radius of curvature of the outside peripheries of the semi-cylindrical portions of the members 13 and 14 at their inner ends is slightly less than the inside radius of the core 12. The small diameter inner end portions of the members 13 and 14 form jaws or clamps 22 and 23, respectively, adapted to be inserted in and frictionally engage the opposite sides of the core 12. The members 13 and 14 have a larger outside radius adjacent their rectangular portions than the radius of the jaws or clamps 22 and 23, and thereby provide shoulders 24 adapted to engage the adjacent end of the core 12.

The members 22 and 23 are clamped in operative engagement with the shaft 11 by means of a set screw 25 extending through the member 13 near its outer end. The screw 25 has an angular recess 26 adapted to receive a correspondingly shaped key 27 whereby the screw is threaded inwardly and outwardly to vary the spacing and to tilt the members 13 and 14, as hereinafter more particularly described, the tilting movement being facilitated by beveling the edges of the element 20 adjacent the recess 16 as best shown in dotted lines in Fig. 1.

Accurate alignment of the member 14 on the shaft 11 is obtained by providing the opposite ends of the member 14 each with a pair of short arcuate projections 28. The projections 28 have their inner faces curved to conform to the curvature and accurately fit the shaft 11. The projections 28 are preferably formed integral with the member 14, and accurate curvature thereof is obtained by machining or by any other process suitable for the purpose.

The described movement of the screw 25 inwardly centers the member 14 relative to the shaft 11 by causing the shaft to closely fit the arcuate projections 28 and also moves the member 13 away from the member 14 until the pivot 15 engages the inner edge of the bore 21, as shown in Fig. 1. The pivot 15 and bore 21 are so positioned that the jaws 22 and 23 are parallel and equally spaced from the axis of the shaft 11 when the pivot is in the position shown. The outer semi-cylindrical surfaces of the jaws or clamps 22 and 23, respectively, fit and frictionally engage the inner periphery of a standard core 12 throughout their length when the pivot is in the position shown. Inasmuch as a large number of cores 12 are successively and repeatedly mounted on the shaft 11, it may happen that the inner diameters of some of the cores may vary slightly from the standard. If such core diameter is slightly in excess of the standard diameter, the jaw 22 will be tilted slightly about the pivot 15 to provide the necessary frictional engagement with the core 12. If the core diameter is slightly less than the standard, the jaws 22 and 23 will uniformly engage the core before the pivot 15 comes to rest on the inner edge of the bore 21, in which case the screw 25 will be threaded to

bring the pivot to the position shown with the result that the core will be very slightly distorted throughout the length of the jaw. The substantially uniform bearing of the jaws 22 and 23 prevent any mutilation of the core and all possibility of slipping of the collar 10 on the shaft 11 is eliminated by reason of the five-point frictional contact provided by the screw 25 and the four arcuate projections 28.

The described relative tilting movement of the members 13 and 14 about the pin 15 adapts the collar 10 to be quickly mounted on the shaft 11 and to be moved longitudinally thereof into operative engagement with the end of the core. The provision of the arcuate projections 28 enable the collar and the core to be accurately centered relative to the shaft. The simplicity of construction of the members comprising the collar and the adaptability of the collar for frictional engagement with the core without mutilation thereof whereby the core may be used repeatedly are important features of the invention.

While the invention has been described as adapted for use with cores forming nuclei for paper rolls and the like, it is obviously adapted for a variety of other uses wherein it is desirable to connect the tubular core with a shaft forming a spindle.

Thus, it will be seen that I have provided an expansion collar of novel and simple construction adapting it for exactly centering tubular members relative to a driving shaft and for frictionally engaging said tubular members with the shaft in a manner such that mutilation of the members and possibility of slipping of the collar relative to the shaft or to the tubular members is eliminated.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. A device for connecting a hollow core with an axial shaft, said device comprising an elongated collar adapted to slip over the shaft, said collar consisting of two substantially semi-cylindrical sections adapted to be inserted in the core, a plurality of arcuate projections on the inner periphery of and at the opposite ends of one of said sections, the outer ends of said sections having contiguous overlapping portions, a pivot extending through said overlapping portions transversely to the axis of the shaft, and means initially operable to rotate the sections relative to each other about said pivot as an axis and thereby to engage the full length of the inserted portions of said sections with the core, said means being subsequently operable to move said sections apart and thereby to clamp the sections in frictional engagement with the core and to clamp said arcuate portions in frictional engagement with the shaft.

2. A device for connecting a hollow core to an axial shaft, said device comprising an elongated collar adapted to slip over the shaft and consisting of two cooperating longitudinally extending sections having contiguous inner end portions of approximately semi-cylindrical shape adapted for insertion in the core, the outer end portion of one of said sections providing a recess in which

an adjacent portion of the other of said sections is positioned, a pivot transverse to the shaft extending through and connecting said outer end portions of the sections, a set screw mounted in 5 one of said sections between the pivot and the core, an arcuate projection on the inner periphery adjacent each end of the other of said sections adapted to closely fit the shaft, said screw when threaded inwardly to engage said shaft 10 being adapted to clamp the semi-cylindrical end of each section in frictional contact with the core and also to clamp said arcuate projections in frictional contact with the shaft.

3. A device for connecting a hollow core to an axial shaft, said device comprising an elongated collar adapted to slip over the shaft and consisting of two cooperating longitudinally extending sections having contiguous inner end portions of approximately semi-cylindrical shape 15 20 adapted for insertion in the core, the outer end portion of one of said sections providing a re-

cess in which an adjacent portion of the other of said sections is positioned, a pivot transverse to the shaft extending through and connecting said outer end portions of the sections, the pivot having a close fit with one of said sections and 5 the other of said sections providing an aperture in which the pivot is movable laterally toward and away from the shaft, a pair of arcuate projections adjacent each end of the inner periphery of one of said sections adapted to closely fit 10 said shaft, and a set screw extending through the other of said sections adapted to engage the shaft at a point intermediate the pivot and the core, said screw being operable to spread the sections apart and then to relatively rotate the 15 sections and thereby to frictionally engage said inserted ends of the sections with the core and to frictionally engage said arcuate projections with the shaft.

ERNEST T. STRAUBEL. 20
